HIGH-TENSION INTERRUPTING DEVICE

Albert Thibaudat, Saint Denis, France, assignor
to Societe Anonyme dite: Forges et Ateliers de
Constructions Electriques de Jeumont, Paris,
France, a corporation of France

Application July 21, 1947, Serial No. 762,369
In France May 21, 1946

Section 1, Public Law 690, August 8, 1946
Patent expires May 21, 1966

10 Claims. (Cl. 200—148)

1

In the practical construction of high tension interrupting devices designed to interrupt moderate currents, such as for example disconnecting switches operating under load or circuit interrupters with moderate interruption power, it is necessary to obtain on one hand a rapid separation of the contacts and on the other hand a considerable spacing between the contacts in the completely open position. The first of these two conditions is justified by the requirement to reduce the duration and energy of the arcs and to accelerate the extinction thereof and it requires important acceleration forces while the second, justified by considerations of security, causes important forces to act throughout the entire length.

It therefore results that these devices exert and accumulate at the closing operation very considerable quantities of mechanical energy producing heavy strains in the control elements and in the devices themselves, rendering difficult their manipulation, bringing about violent shocks which risk damaging the insulators, producing dangerous rebounds, etc.

On the other hand the control of such switches is to be effected through the intermediary of insulating elements subjected to bending or torsional strains which are, as is known, undesirable. These disadvantages are particularly troublesome in the case of air blast switches, and the present invention, also applicable to non-blowing devices, has for an object avoiding these disadvantages by an improved arrangement wherein the rapid movement of the movable contacts, the action of the air blast and the general method of operation, all factors which favor the rapid extinction of the arcs, are only acting during a period which is relatively short compared to the entire duration of the disconnection.

The invention also has for an object increasing the breaking power of pneumatic disconnection devices operating without a separated compressor, simplifying their construction and permitting their operation with relatively high tensions.

A further object of the present invention is to provide a kinematic system for interrupting devices which is designed so as to effect successively two or more distinct movements of different nature. The first movement is a relatively rapid movement but restricted in scope for the actual interruption or closure of the circuits and the other movements are more slowly accomplished through a greater distance for securing the safety disconnection of the controlled circuits.

2

A further object of the invention is to provide means whereby the first movement is a rapid rectilinear translation, sufficient for the complete interruption of the controlled circuit, while the second is a rotation of the movable parts. When pneumatic extinguishing is applied it preferably takes place only during the first movement.

A still further object of the invention is to avoid not only the disadvantages indicated above but also secure several new advantages which will be set forth below in the description of the structural examples which relate to disconnecting switches operating under load and circuit breakers having an arc blowing system with concentric channels operating without separate compressors.

Other objects of the invention will appear from the description which follows describing various possible modifications.

In the drawings, wherein similar reference characters indicate like parts, Fig. 1 is a side elevational view with parts in section of one form of the invention showing the contacts in closed position.

Fig. 2 is a side elevational view with parts in section showing the position of the elements at the termination of the first translational movement for securing the actual interruption of the circuit.

Fig. 3 is a view similar to Fig. 2 illustrating the position of the elements in the completely open or safety disconnection position.

Fig. 4 is a partial cross sectional view on a larger scale of the contacts.

Fig. 5 is a side elevational view with portions broken away and with a partial wiring diagram of a modified construction, and

Fig. 6 is a view similar to Fig. 5 of a still further modification.

Referring to Fig. 1, the porcelain insulator 1 supports the group of fixed contacts 2 comprising the main contacts 3 and the resilient interrupting contact 4 shown in Fig. 4. The porcelain insulator 5 supports the pivot 6 for the movable elements. These elements are formed essentially by a metallic tube 7 closed by a plug 7A and carrying the piston 8 as well as the movable cylinder 9 which may be displaced with relation to the piston 8.

Preferably the length of the cylinder 9 is relatively small compared to its diameter. The cylinder is constantly urged towards the pivot 6 by a strong concentric spring 10 whose upper end is attached to an enlargement 11 provided upon the

upper portion of the cylinder. The lower end of the spring 10 is attached to the ring 12 which is fixed by two ears 12A to the common pivot 6.

The cover 8A of the cylinder 9 (Fig. 4) carries the movable contact 13 of tubular form which cooperates with the main contacts 3. At the interior of the tubular contact 13 whose end 13' may be made of an insulating material as shown is the conducting tube 14 whose upper end 14' of reinforced construction cooperates with the resilient interrupting contact 4. The contact 4 carrying a guide rod 4'' has fixed thereto the insulating element 4' whose lower surface is in contact with the end 13' of the tube 13. The elements 4, 4'' and 4' are urged downwards by a compression spring as shown; the downward movement of the contact 4 is limited by a stop upon the upper end of 4''.

The conducting tube 14 is fixed to the elements 9 and 13. It has at its lower portion some longitudinal slots 15, Fig. 1, while the tube 7 has in the neighborhood of these slots some apertures 16 which open into the extension 17 of the cylinder 9 arranged to slide along the tube 7.

The extension 17 carries two hinges 18 (Figs. 2 and 3) to which are attached two links 19, connected to the upper ends of the two angular levers 20 whose lower ends are driven by the insulated connecting rod 21. This connecting rod is actuated by an appropriate control mechanism not shown, or by hand.

The whole device is connected to the controlled circuit by the leads M and N fixed upon the terminals *m* and *n*.

In order to simplify the drawing there has not been shown thereon the usual means such as flexible connections, the sliding contacts, etc., for transmitting heavy currents across the different elements of the apparatus.

The operation of the apparatus may be carried out by hand as a disconnecting switch or automatically as a circuit breaker. In order to describe its operation the first case is assumed. The movable elements occupying the completely opened position shown upon Fig. 3, a lever or wheel (not shown) is manually operated to strain a spring (not shown) and to move the insulating connecting rod 21 towards the right.

The lever 20 passes from the position A to the position B and all the movable elements swing freely as a unit towards the axis EB (Fig. 3) to reach the position shown upon Fig. 2. In this position the rotation of the tube 7 is stopped by the abutment 22 provided upon the lower porcelain support 5. This rotation which has no resistance to overcome takes place slowly and its termination by the abutment 22 is carried out without shock.

Then the operating lever is turned by hand or by a control wheel (not shown) in the opposite direction which liberates the spring (not shown) mentioned above and this spring rapidly moves the angular lever 20 into the position C. The toggle joint 19, 20 straightens and raises the hinges 18 with the cylinder 9, 17 which slides upwardly along the tube 7 while stretching the spring 10. The end 13' of the contact tube 13 contacts the element 4' and the end 14' of the tube 14 contacts the resilient contact 4. The elements 4 and 4' are raised and the tube 13 penetrates into the assembly 2 while establishing the definite connection with the main contacts 3 (Fig. 1).

In the case of the manual control assumed above the toggle joint 19, 20 passes preferably

slightly past its dead point and the apparatus is in its stable closing position. In order to unlock it suffices to break the toggle.

In the case of automatic control the angular lever 20 is preferably moved into the position C which is adjacent the position D of the dead point but without passing it. The apparatus then tends to open automatically and the insulating connecting rod 21 is subjected to a small compression force. It may then be retained in this position (shown upon Fig. 1) by an appropriate locking device which may be unlocked by hand, by a relay, by interrupting a control circuit or by any other means.

The control mechanism of the insulating connecting rod 21 may comprise any known means which will secure a free tripping.

In order to facilitate the relative movement of the cylinder 9 with relation to the piston 8 during the closing operation, appropriate pneumatic elements such as suitable inlets or valves (not shown) are provided and are arranged to open during the upward movement of the cylinder 9 and prevent any pneumatic braking at closing. By way of security any appropriate locking means such as cams, pawls, etc., may be provided to prevent the premature straightening of the toggle joint 20, 19 during movement through the course A—B. This precaution is not indispensable since the correct succession of movements is assured through the considerable force of the spring 10 which only comes into play during movement through the course B—C.

The unlocking is brought about according to this case, either by a slight displacement towards the left of the insulating connecting rod 21 when the dead point of the toggle joint has been passed during the course of closing or by the unlocking of the locking device (not shown) when the dead point has been reached.

During the circuit interruption the apparatus passes quickly from the position of Fig. 1 to that of Fig. 2. During the rectilinear translational movement, the lever 20 passes from position C to position B, the cylinder 9 urged by the spring 10 moves downward and the outside tube 13 leaves the main contacts 3 after which the tubular contact 14' separates from the resilient interrupting contact 4 producing the interruption arc.

At the beginning of this movement the elements 4 and 4' follow through a certain distance the elements 13' and 14' so that the upper openings of these movable elements remain temporarily closed. When the elements 4 and 4' are finally stopped in the position shown upon Fig. 2 by the abutment provided upon the rod 4'', the air compressed at the top of the piston 8 escapes through the annular channel between the tubes 13 and 14 (Fig. 4) while the lowering of pressure created under the piston 8 sucks the surrounding air through the tube 14, the slots 15 and the apertures 16, as shown by the arrows upon Fig. 4.

These slots 15 are provided in order to maintain open the apertures 16 when the cylinder 9 and its inner tube 14 are in the lowest position, so that the space under the piston 8 is always in communication with the opening of the contact element 14'.

Experience shows that with this blowing method, as well as with simplified modifications thereof, the arc is quickly extinguished during a relatively short translation, which permits the use of a small cylinder 9 and consequently small and noncumbersome movable elements.

This rapid interrupting movement being achieved, it is followed by the further rotation of the lever 20 towards the position A and all the movable elements return to the complete opening position shown upon Fig. 3. This disconnecting movement takes place at reduced speed and it is therefore accomplished without shock and without exposing the porcelain support 5 to strains.

The voltage of the controlled circuits and the interrupting power of the interrupting devices above set forth may be increased substantially by the use of two or more devices analogous to those described above; it is also possible to improve their performance by appropriate interrupting resistances.

The improved means secure in a simple and economical way autonomous circuit interrupters with self compression, that is, operating without any special source of compressed air and nevertheless having a quite high interrupting power.

Upon Fig. 5 there is shown an interruptor with self compression comprising two movable equipments connected in series and analogous to those described above. In order to simplify the drawing there has not been shown thereon either the operating elements of the movable elements or the resilient elements, such as the springs which actuate the blowing means. All of these elements may be arranged as set forth above or in any other equivalent way.

The equipment shown comprises two fixed contact elements 21 and 22 supported by the insulators 23 and 24 and connected to the outer leads 25 and 26. These two fixed elements may comprise contacts of any nature, rigid or resilient, and particularly appropriate interrupting contacts, schematically shown at 21' and 22'.

They cooperate with two movable contact arrangements 27 and 28 having suitable blowing means of any nature, supported by the movable cylinders 29 and 30. These latter are preferably of relatively large diameter to secure during a relatively short distance with relation to their pistons 31 and 32 sufficient compression of the inclosed air.

The relative displacement of the cylinders 29 and 30 with relation to the pistons 31 and 32 is taken care of by elastic means such as springs similar to those of Fig. 4 which have not been shown. These means urge the two cylinders towards one another when they have been freed by any desired unlocking system.

The pistons 31 and 32 are connected by a pivotally mounted support 33 mounted upon the pivot 34 and the insulator 35. A resistance 36 may be connected as shown between the movable elements and one of the terminal connections. Fig. 5 shows the apparatus in the locked position in which the circuit is closed and the opening means such as the springs mentioned above are strongly strained.

In order to effect interruption, the opening means are released which rapidly displace the cylinders 29 and 30 with their tubular contact elements 27 and 28 towards the pivot 34. At the start of their travel the elements 27 and 28 are followed by the resilient contact elements 21' and 22' and the air filling the cylinders 29 and 30 is subjected to a rapid compression by the pistons 31 and 32 which remain for the moment immovable.

The contacts 21' and 22' are then stopped while the elements 27 and 28 continue their vertical travel and the arcs which result are effi-

ciently blown out by the compressed air blast. When a definite extinction of the arcs is thus obtained during a relatively short rectilinear travel of the contacts 27 and 28 the support 33 effects a rotation in clockwise direction to occupy the disconnecting position FF' in which the movable elements occupy the position shown by dotted lines.

When an interrupting resistance 36 is used one of the arcs is shunted by the resistance which is acting usefully during the separation of the corresponding contacts 28 and 22' in order to damp the oscillations of the recovery voltage and to increase if necessary the interrupting power.

15 The shunted arc may be started a little before the nonshunted arc.

In the modification shown upon Fig. 6 the pistons 31 and 32 are supported by the separate supports 37 and 38 pivoted at 39 and 40. The pivot 39 is provided upon the fixed contact element 22 and the pivot 40 as well as the terminal connection 26 are supported by the insulator 41. The resistance 36 may be connected between 22 and 40 for example.

25 The two movable units 27, 29, 31 and 28, 30, 38, carry out in this arrangement separate movements in order to occupy finally the disconnecting positions shown in dotted lines at G and G'.

The mechanism designed for producing the successive movements of the movable elements may be analogous to that of Figs. 1 to 3 or be arranged in any other appropriate way. For example, the correct succession of the various interrupting and disconnecting movements may be secured with the aid of appropriate cams and thereby eliminate the springs which are attached directly to the movable cylinders. A resilient element for actuating the cylinders for the first movement corresponding to the interrupting of the arcs may be in this case located in the common control mechanism and may be arranged to intervene only during the corresponding movement.

In place of displacing the cylinders 29 and 30 with relation to the pistons 31 and 32, the pistons may be displaced to secure the extinction of the arcs by a rectilinear movement of the contacts 21 and 22' so as to space them from the blowing elements 27 and 28 after which the disconnection may be secured by an appropriate displacement of the elements 21 and 22 or by a rotation of the cylinder as has been set forth above.

Other combinations of two or more movements may be provided and other modifications of the means described may thereby be obtained.

It is also obvious that the blowing method described may be modified. For example, cylinders and pistons may be eliminated or replaced with the action of a gas produced in a known manner by suitable bodies under the effect of the arc, etc.

In place of a rapid rectilinear movement for the actual interruption followed by a slow rotative movement for the disconnection, two or more successive rectilinear movements may also be used. One movement with the blast may be rapid, for example, and the other slow. Also two or more successive rotative movements, or the interruption may be carried out by rotation and the disconnection by translation. It is obvious that other modifications are possible.

The apparatuses described and their modifications may be used and arranged in any appropriate way according to the conditions of use in order to operate, for example, as disconnecting

switches operating under load or as automatic circuit interrupters with a reasonable interruption power.

The invention presents particularly the following advantages.

The mechanical forces are only applied during a portion of the travel (through BC) which reduces by a very large proportion the mechanical energy accumulated and facilitates operation of the apparatus.

The control is carried out through the intermediary of an insulating connecting rod 21 which is only exposed to traction efforts or compression which permits lightening the construction and securing a greater security.

The porcelain supports for the movable elements are not subjected to violent shocks which also increases the security of operation.

The control elements shown and not shown such as the connecting links, locking devices, etc., may be diminished in weight and simplified.

The pneumatic blowing elements being reduced in weight and cumber someness in that they only come into action during a short interruption travel permit the inertia of the movable elements to be reduced and the circuit interruption to be rapid.

The blowing elements having an appropriate diameter and being located very close to the contacts, the blowing action acts very rapidly and upon separation of the contacts, it attains full efficiency.

In the following claims the term disconnection means the separation of the contacts to a safe position such as shown in Fig. 3.

I claim:

1. A high tension circuit interrupter comprising a fixed contact and a movable contact, said movable contact comprising a pivotally mounted support, a piston on said support, a cylinder for said piston slideable on said support, coaxial tubular members fixed to said cylinder forming the contact elements cooperating with said fixed contact, means for moving said cylinder and contact elements toward and away from said fixed contact in a rapid rectilinear movement to bring about the actual interruption and closure of the circuit, said movement causing a relative movement between said piston and cylinder placing air under pressure which is expelled through said tubular members for extinguishing the arc formed upon the interruption of the circuit and means for swinging said support and associated elements to disconnection position at the termination of the rectilinear interrupting movement.

2. A high tension circuit interrupter comprising a fixed contact and a movable contact, said movable contact comprising a pivotally mounted support, a piston on said support, a cylinder for said piston slideable on said support, coaxial tubular members fixed to said cylinder forming the contact elements cooperating with said fixed contact, resilient means interconnecting said cylinder and support, toggle means for moving said cylinder and contact elements to closure position and thereby placing said resilient means under tension, means for releasing said toggle means so that said cylinder is retracted rapidly along said support by said resilient means said movement causing a relative movement between said piston and cylinder placing air under pressure which is expelled through said tubular members for extinguishing the arc formed upon the interruption of the circuit and means for

swinging said support and associated elements to disconnection position at the termination of the rectilinear interrupting movement.

3. A high tension circuit interrupter comprising a fixed contact and a movable contact, said movable contact comprising a pivotally mounted support, a piston on said support, a cylinder for said piston slideable on said support, coaxial tubular members fixed to said cylinder forming the contact elements cooperating with said fixed contact, resilient means interconnecting said cylinder and support, toggle means for moving said cylinder and contact elements to closure position and thereby placing said resilient means under tension, means for releasing said toggle means so that said cylinder is retracted rapidly along said support by said resilient means said movement causing a relative movement between said piston and cylinder placing air under pressure which is expelled through said tubular members for extinguishing the arc formed upon the interruption of the circuit, the inner coaxial member of said coaxial tubular members having communication with the suction side of said piston so that a suction is also exerted to extinguish said arc and means for pivoting said support and associated elements to disconnection position at the termination of the rectilinear interrupting movement.

4. A high tension circuit interrupting and disconnecting device comprising a fixed contact and a co-operating movable contact unit, said contact unit being formed by a pivotally mounted support, a piston fixed upon said support, a cylinder for said piston slideable on said piston, coaxial nozzle members carried by said cylinder and forming the movable contact proper and means for positively separating said movable contact from said fixed contact first in a rapid rectilinear translation to bring about the actual interruption of the circuit by a rapid contact separation and by an air blast resulting from the relative movement of said cylinder, and then in a slower rotation of said support and of the associated contact unit in order to further increase the said contact separation.

5. A high tension circuit interrupting and disconnecting device having a fixed contact and a co-operating movable contact unit, said unit comprising a pivotally mounted support, a piston on said support, a movable cylinder cooperating with said piston, coaxial tubular members fixed to said cylinder and forming a movable contact, resilient elements interconnecting said cylinder and support, positive mechanical means for moving said cylinder with the said associated movable contact into the closed position and thereby placing said resilient elements under tension and means for releasing said resilient elements, whereby said movable contact and cylinder are first retracted rapidly along said support producing air blasts through said tubular members for extinguishing the arc formed upon the separation of contacts, said mechanical means being arranged for producing after said retracting movement a rotation of said support and of its associated elements in order to further increase the separation of said contacts.

6. A high tension circuit breaking and disconnecting device comprising two fixed contacts and two cooperating movable contacts connected in series, each of said movable contacts comprising a pivotally mounted support, a piston on said support, a cylinder for said piston slideable on

said support, coaxial tubular members fixed to said cylinder forming the contact elements co-operating with said fixed contact, resilient means interconnecting said cylinder and support, toggle means for moving said cylinder and contact elements to closure position and thereby placing said resilient means under tension, means for releasing said toggle means so that said cylinder is retracted rapidly along said support by said resilient means, said movement causing a relative movement between said piston and cylinder placing under pressure the air which is expelled through said tubular members for extinguishing the arc formed upon the interruption of the circuit, the inner coaxial member of said coaxial tubular members having communication with the suction side of said piston so that a suction is also exerted to extinguish said arc, and means for pivoting said support and associated elements to disconnection position at the termination of the rectilinear interrupting movement.

7. A high tension circuit breaking and disconnecting device comprising two fixed contacts, two cooperating movable contacts and a pivotally mounted support carrying both said movable contacts, each of which comprises a piston on said supports, a cylinder for said piston slideable on said support, coaxial tubular members fixed to said cylinder forming the contact elements co-operating with said fixed contact, resilient means interconnecting said cylinder and support, toggle means for moving said cylinder and contact elements to closure position and thereby placing said resilient means under tension, means for releasing said toggle means so that said cylinder is retracted rapidly along said support by said resilient means, said movement causing a relative movement between said piston and cylinder placing air under pressure which is expelled through said tubular members for extinguishing the arc formed upon the interruption of the circuit, the inner coaxial member of said coaxial tubular members having communication with the suction side of said piston so that a suction is also exerted to extinguish said arc, and means for pivoting said support and associated elements to disconnection position at the termination of the rectilinear interrupting movement.

8. A circuit interrupting and disconnecting device comprising a movable contact including an axial conducting tube forming the contact element proper and an annular channel, positive mechanical driving means to effect during the circuit interruption a rapid arc interrupting translation of said movable contact, as well as a less rapid transverse disconnecting movement of the same contact, a cylinder supporting said movable contact, a cooperating piston, means for displacing said cylinder with respect to said piston during said translation only, and means for interconnecting respectively both parts of said cylinder with said conducting tube and said annular channel, whereby an air-blast and an air-suction are produced.

9. A high tension circuit interrupting and dis-

65

connecting device comprising a fixed contact and a cooperating movable contact structure including a tubular element, an axial conducting tube forming the contact element proper and an annular channel surrounding said tube, said movable contact having a pivotally mounted support, a piston fixed upon said support, a movable cylinder for said piston, carrying said movable contact structure, the said tube being connected to one part of said cylinder and the said annular channel being connected to the other part of said cylinder, resilient members interconnecting said cylinder and support, mechanical means for positively operating said cylinder and movable contact to a position in which said resilient means are placed under tension and the circuit is closed, and means for releasing said resilient members whereby two successive movements are produced, the first being a rapid translation resulting in a separation of the contacts and producing an air blast through said annular channel and an air suction through said conducting tube in order to extinguish the arc, and the second being a pivotal rotation of said support adapted to increase substantially the separation of contacts obtained during the said translation.

10. A high tension circuit breaker comprising a fixed contact and a cooperating movable contact, said movable contact comprising a pivotally mounted support, a piston on said support, a cylinder for said piston slideable on said support, coaxial tubular members fixed to said cylinder forming the movable contact elements co-operating with said fixed contact, means for moving said cylinder and tubular members away from said fixed contact in a rapid rectilinear movement to bring about the actual opening of the circuit, means upon said fixed contact adapted to close said tubular members on a part of said rectilinear movement, whereby the air filling said cylinder is compressed until said tubular members are opened and said compressed air is expelled through said tubular members for extinguishing the arc of interruption of the circuit, and means for swinging said support and associated elements to disconnection position at the end of said rectilinear movement, whereby the distance between said cooperating contacts is further increased.

ALBERT THIBAUDAT.
